UNITED STATES PATENT OFFICE

WILLIAM J. DE WITT, OF AUBURN, NEW YORK, ASSIGNOR TO THE SHOE FORM CO., INC.,
OF AUBURN, NEW YORK, A CORPORATION OF NEW YORK

EXPANSIBLE SHOE FORM

Application filed March 27, 1928. Serial No. 265,000.

This invention pertains to expandible forms or trees designed to keep footwear plumped out and free from wrinkles while on exhibition, during shipment or storage, and in the intervals between periods of use, and for specific illustration is herein disclosed as comprising a hollow, resilient, thin-walled shell such as may conveniently be made of sheet celluloid or equivalent material in accordance with well-known methods of procedure, for example, that described in my Patent No. 1,585,284, May 18, 1926,—although in its broader aspects it is not necessarily limited to shells of this particular type of material. In my Patent No. 1,646,016, October 18, 1927, I have described an expandible form comprising such a thin-walled shell adapted to fit into the forward portion of a boot or shoe and provided with a toggle arrangement for expanding the form and for holding it locked in expanded position. While the forms disclosed in the last-named patent are very useful and efficient for the purpose, the toggle arrangement,—comprising a plurality of relatively movable parts, adds materially to the weight of the form and to the cost of making it, while the toggle mechanism is capable of locking in but one expanded position.

In accordance with my present invention I provide an expandible form comprising a thin-walled shell together with expander means which in its simplest embodiment may be a simple spring reacting against the opposite sides of the form but which, in its preferred embodiment comprises a movable expander member, preferably a transverse (resilient or rigid) strut or bar reacting against opposite sides of the form and having adjustable interlocking engagement with an element of the shell at one or both of its ends. With this expander member I may combine a resilient thrust bar adapted to extend longitudinally of the shoe and to engage the inner surface of the counter portion of the shoe, thereby exerting forward pressure against the shell, tending to expand the latter and to force it into the toe of the shoe, but when the expander adjustably interlocks with the form, I prefer to employ interlocking elements such that the forward pressure of the resilient bar

can not produce undue expansion of the form.

In addition to or in substitution for the adjustable transverse expander member, I sometimes employ an expandible element, for example, an arched or U-shaped rod or wire of resilient material such as steel, celluloid, or a combination thereof, extending around the toe portion of the shell from one side to the other of the latter, thereby adding to the inherent stiffness and resiliency of the shell, and this rod or wire may be so associated with the shell as to strengthen the toe of the latter and to impart a neat and smooth finish to the front end of the shell.

In the accompanying drawings I have illustrated, by way of example, a desirable embodiment of my invention, together with various modifications thereof, but with the understanding that the invention is not necessarily limited to the specific arrangements chosen for illustration of the broad principle of the invention.

In the drawings

Fig. 1 is a side elevation of my improved expandible form, indicating in broken lines the counter portion of a shoe with which the resilient rearwardly extending thrust-bar of the form engages;

Fig. 2 is a plan view of the form of Fig. 1, with the thrust bar broken off;

Fig. 2^a is a fragmentary section on line 2^a—2^a of Fig. 2;

Fig. 3 is a fragmentary section on the line 3—3 of Fig. 2;

Fig. 4 is a fragmentary section on the line 4—4 of Fig. 2;

Fig. 4^a is a section similar to that of Fig. 4, but illustrating a modification;

Fig. 5 is a plan view partly in section of a modified construction;

Fig. 6 is a fragmentary section on the line 6—6 of Fig. 5;

Fig. 7 is a fragmentary section on the line 7—7 of Fig. 5;

Fig. 8 is a fragmentary bottom plan view of a form showing a modified construction of the interlocking elements;

Fig. 9 is a plan view partly in section of a further modification;

Fig. 10 is a section on the line 10—10 of Fig. 9;

Fig. 11 is a bottom plan view, partly in section, showing a further modification;

5 Fig. 12 is a fragmentary section on the line 12—12 of Fig. 11;

Fig. 13 is a bottom plan view showing another modification of the form;

10 Fig. 14 is a bottom plan view, illustrating a still further modification; and

Fig. 15 is a vertical section on the line 15—15 of Fig. 14.

Referring particularly to Figs. 1 to 4 inclusive, the numeral 1 designates a hollow thin-walled resilient shell adapted to fit into the toe portion of a boot or shoe. This hollow shell has a smoothly continuous outer surface shaped to conform to the interior of the shoe and is preferably made of sheet celluloid or similar material by a process such for example as is disclosed in my Patent No. 1,585,284, dated May 18, 1926, although so far as the present invention is concerned the mode of preparation of this hollow resilient shell is immaterial. As more fully pointed out in my patent just referred to, the very thin and uniformly resilient character of this shell furnishes an internal support for the shoe upper which does not substantially detract from the normal feel of the upper, although keeping it smooth and plumped out.

The shell 1 is preferably provided with an inturned marginal bottom flange comprising 35 a narrow toe portion 2, but gradually widening rearwardly from the toe to form the wide side flange members 3 and 4. While this flange as here shown is continuous, it may be desirable, under certain circumstances, to 40 separate the flange into sections or tab-like portions, and I contemplate that this may be done without departing from the spirit of the present invention. This flange is smooth and substantially free from wrinkles 45 at the toe, as well as at the sides, providing a flat surface for contact with the shoe bottom.

While the shell 1, made as above suggested of sheet celluloid or similar material is quite 50 resilient, I prefer under many conditions to increase the stiffly resilient character of the form by arranging the arched or substantially U-shaped expander member in the toe portion of the shell. Preferably this expander member comprises a rod (solid or tubular) of suitable diameter and of resilient material which if desired may be bent approximately to shape before applying it to the form. This member, after bending, is 55 laid into the angle between the flange 2 and the body of the shell proper, and secured in position in any desired manner. For example, if the shell be of celluloid, I may make the expander member of celluloid, and 60 before applying it to the shell I dip it in a

celluloid solvent, for example acetone, which forms a film of celluloid solution on its surface. After application, this film hardens and forms a homogeneous and integral union between the expander member and the shell. 70 Obviously, in place of the celluloid expander element I may use an expander of wire or any other desired material. As shown in Figs. 1 to 4, I prefer to employ a composite expander member comprising the tubular celluloid rod 5, having a steel or other resilient wire 6 passing through it. The tubular celluloid member 5 may be secured to the body of the shell in the manner above suggested, and thus forms a convenient means 80 for retaining the more highly resilient metallic wire 6. As shown in Fig. 2, the ends of the wire 6 may project beyond the ends of the enclosing celluloid tube to any extent desired. I contemplate that, for certain purposes, the tube may be shortened up until it is of sufficient length merely to hold the wire 6 in position.

The wider portions 3 and 4 of the bottom flange of the shell are provided with slots 7 and 8, preferably of arcuate or curved contour, and provided with one or more, preferably a plurality of notches 9 and 10 respectively, in their outer edges for cooperation with a second expander member 11, preferably also of arched or curved contour, which provides for positively adjusting the width of the form. While the arched form of the member 11 is preferred, it may be straight as shown at 11^a in Fig. 4^a. This expander 90 11 may be of resilient material if desired, although preferably quite stiff, and may conveniently be made from steel or brass wire, and is preferably furnished with loops 12 and 13 at its opposite ends which receive pins 14 and 15 respectively, engaging the slots 7 and 8. Preferably the pins 14 and 15 take the form of rivets having heads at opposite ends which prevent their escape from the loops 12 and 13 and from the slots 7 and 8. 95 These rivets also constitute locking elements, adapted to engage or interlock with the notches 9 and 10, and when interlocked with such notches to prevent longitudinal movement of the ends of the expander with respect to the shell.

100 Preferably the expander bar 11 is provided with a loop 16 at any desired point for the reception of the forward end 17 of a thrust bar 18. This thrust bar is preferably 105 of resilient material and is arched or bowed upwardly and extends longitudinally of the form to a sufficient distance to permit its rear end 19 to engage the inner surface 20 of the counter of a shoe. Preferably the end 19 may be looped or curved to provide a 110 smooth finish for engagement with the shoe surface, and the forward end 17 is looped for pivotal connection to the bar 11. Desirably the bar 18 consists of a tube of celluloid 115 120 125 130

or the like enclosing a resilient core of metallic wire.

Springs S and S' may if desired be provided, such springs tending to move the expander bar in a direction such as to expand or contract the form, as may be preferred. As shown, the springs tend to move the pin 14 toward the forward end of the slot 7, and the pin 15 toward the rear end of the slot 8, the expander bar 11 extending transversely across the form. The form is now pushed into the toe portion of the shoe, the expander 11 being first swung in a counter-clockwise direction as viewed in Fig. 2, either by direct application of the fingers of the user or by force applied through the thrust bar 18, thus contracting the form transversely. This movement of the expander 11 may take place about one of its ends as a pivot, or about its center. When the form is properly positioned in the shoe, the expander is swung or permitted to swing by the action of springs S and S', and the thrust bar 18, in the opposite or clockwise direction, (thus expanding the form) until one or both of the pins 14 and 15 snaps into one of the notches 9 or 10, thus locking the bar in adjusted position and preventing its return to normal position under the action of the compressive force of the shoe. However, by the application of longitudinally applied force, preferably at one or the other end of the expander 11, it may be swung in the opposite direction to permit the form to contract as above described. If the springs S and S' are not provided, the expansion of the form is accomplished merely by pushing the shell 1 into the toe of the shoe and snapping the thrust bar 18 into the shoe against the counter portion, the pressure of the resilient bar 18 being usually sufficient to swing the expander member 11 to the desired extent.

In order to facilitate movement of the bar 8 to its operative or expanding position, I may, as indicated in Fig. 8, provide the flange 3^a with a slot 7^a having notches 9^a which are unsymmetrical, their rear faces being substantially perpendicular to the axis of the form, while their forward faces are gradually inclined, thus providing easy cam surfaces for engagement with the pin as it moves in the forward direction. Obviously the corresponding slot on the other side of the form would have its notches arranged in the reverse direction.

While as above described I prefer to provide the form with slots 7 and 9 at its opposite sides, I may, as shown in Fig. 5, provide a slot at one side only. Thus in Fig. 5 the shell 1^b has a bottom flange comprising the narrow forward portion 2^b and the wide rear portions 3^b and 4^b. The transversely extending expander member 11^b is furnished with an eye or loop 13^b at one end

which receives a pivot stud or rivet 15^b for pivotally securing the member 11^b to the flange 4^b. The flange 3^b is furnished with a slot 7^b having one or more notches 9^b in its outer edge, and this slot receives the locking stud or rivet 14^b which cooperates with the slot 7^b and notches 9^b in the same way as the corresponding stud 14 above described. In the arrangement shown in Fig. 5 the thrust bar is omitted, and expansion of the shell is produced by direct application of the fingers of the user to the member 11^b, or by the action of a suitable spring S^b.

In this instance, as well as in the device shown in Fig. 2, the bottom flange is very narrow at the toe portion, being in fact no wider, and preferably not so wide as the diametral thickness of the arched expander member 5^a. As shown in Fig. 6, this expander member 5^a is of cylindrical section and preferably of celluloid, as above described, and the extreme edge 20 of the flange 2^a is beveled to fit snugly against the member 5^a, so that the latter constitutes in effect a beaded or ribbed edge at the toe portion of the shell.

Referring now to Fig. 9, the shell 1^c has the inturned bottom flange comprising the narrow forward portion 2^c and the wide rear portions 3^c and 4^c. In this embodiment of the invention the entire expansive effect is produced by the arched expander member 5^c, which is seated in the angle between the flange and the shell proper, and which extends well toward the rear portion of the shell. This expander member is, as above described, of tubular form, enclosing the resilient metallic core 6^c whose ends preferably project beyond the tubular enclosing member and are bent or looped as shown at 21 to provide a smooth finish.

In Fig. 11 the shell 1^d has the bottom flange comprising the forward part 2^d and the rear parts 3^d and 4^d. In this case also a single expander member 11^d is employed, this member being arched horizontally and of resilient character, and having its opposite ends seated in tubular members 5^d secured to the flanges 3^d and 4^d respectively. These tubular members 5^d may be of celluloid and are integrally united to the flange members in the same way as the member 5 above described.

In Fig. 13, the shell 1^e has the bottom flange comprising the parts 2^e, 3^e and 4^e, and the transverse arched expander member 11^e. This member 11^e is provided at its opposite ends with loops which receive rivets or pivot pins 14^e and 15^e respectively attaching it to the flange members 3^e and 4^e. The member 11^e is disposed in a substantially horizontal plane, and is of resilient character so that it opposes approach of the opposite sides of the shell.

In Figs. 14 and 15, the shell 1^f has the bot-

tom flange comprising the parts 2^t, and 3^t, and 4^t, and is provided with a transverse arched expander member 11^t which is disposed in a substantially vertical plane. This member 11^t has its opposite ends seated in tubular members 5^t which may, for example, be of celluloid and integrally united to the flanges 3^t and 4^t respectively in any desired manner, for example as described with respect to the tubular member 5.

10 As shown, the normal resiliency and stiffness of the shell is enhanced by the addition of a stiffly resilient member which opposes approach of the opposite sides of the shell, and which may and preferably does exert a positive outward expansive force tending to spread the shell beyond its normal width. As shown in Figs. 1 to 8 inclusive, I may provide an expander member which is adjustable whereby positively to vary the width of the shell, and in conjunction with this adjustable expander element I provide locking means capable of holding the expander member in any one of a plurality of adjusted positions.

15 This arrangement, whereby the expander element may be locked in a plurality of positions, is preferable to an arrangement in which an ordinary toggle is employed, since the latter provides but a single position of 20 fixed adjustment. The expanding and locking means which I have here disclosed is of the simplest possible form, and adds very little to the weight of the shell or to the expense of manufacturing it; it takes up very little room within the shoe so that it does not 25 conceal the interior of the shoe to any substantial extent, and in conjunction with a smoothly continuous shell which bears against the entire inner surface of the shoe upper at the forepart of the latter, it provides expansion means capable of exerting a gentle and substantially uniform pressure over the entire surface of the shoe upper without tendency to bulge the latter at any 30 particular point; and while the form is primarily intended for use with a shoe of a given size, the range of expansion is such that the form may be used with shoes within a considerable range of sizes, and readily accommodates itself to shoes of different style and 35 pattern.

40 While I have here shown and described certain specific embodiments of the invention, I wish it to be understood that the invention is not thus limited, but that variations in detail and the substitution of equivalents for elements here shown is within the scope of the invention.

I claim:

45 1. An expandible shoe form comprising a hollow resilient shell having a smoothly continuous outer surface engageable with the inner surface of a shoe, said shell having inwardly directed flange members at its opposite sides, one at least of said flanges having

50 a slot therein, an expander member having a locking element disposed within said slot, and means providing a pivotal connection between the expander member and the opposite flange, the slotted flange being provided with locking elements cooperating with the locking element of the expander member to retain the latter in adjustable position.

55 2. An expandible shoe form comprising a hollow resilient shell having a smooth outer surface engageable with the inner surface of a shoe, said shell having inwardly directed flange members at its opposite sides, one at least of said flange members having a curved slot 60 therein, one edge of the slot having a plurality of spaced locking notches, an expander bar provided with a locking element movable longitudinally of the slot and engageable with any selected one of the notches, and means constituting a pivotal connection between the expander bar and the opposite flange.

65 3. An expandible shoe form comprising a hollow resilient shell for insertion within a shoe, said shell having inwardly directed flange members at opposite sides, an expander bar extending transversely of the shell, means constituting a pivotal connection between one end of the bar and one of the flange members, the opposite flange member having a curved slot therein, one edge of the slot having a plurality of spaced notches 70 therein, and a locking pin carried by the other end of the bar, said pin being movable along the slot and engageable with any selected one of said notches.

75 4. An expandible shoe form comprising a hollow resilient shell for insertion within a shoe, said shell having inwardly directed flange members at opposite sides, an expander bar extending transversely of the shell, said bar having a loop at each end, each flange having an elongate slot therein, the edge of each slot having a plurality of notches, and a pin slidable along each slot, said pins engaging the loops at opposite ends of the expander bar, respectively.

80 5. An expandible shoe form comprising a hollow resilient shell for insertion within a shoe, said shell having inwardly directed flange members at opposite sides, an expander bar extending transversely of the shell, each flange having a curved slot provided with at least one notch in its outer edge, and a headed pin carried by each end of the expander bar, said pins sliding, respectively, 85 in the slots in the opposite flanges.

85 6. An expandible shoe form comprising a hollow resilient shell for insertion within a shoe, said shell having inwardly directed flange members at opposite sides, an expander bar extending transversely of the shell, said bar having adjustable interlocking connections at its opposite ends with the respective flanges, and a resilient thrust bar united 90

at one end to the expander bar and provided at its opposite end with means for engagement with the inner surface of the counter portion of the shoe, said thrust bar comprising a resilient metallic wire encased in a tube of celluloid.

7. An expansible shoe form comprising a thin-walled hollow resilient shell having a smoothly continuous outer surface engageable with the inner surface of a shoe, and an expander element extending transversely across the shell, one end at least of said expander being movable longitudinally of the shell whereby to vary the width of the shell, 10 said shell and the expander having interengaging elements adapted to retain the expander element in any selected one of a plurality of positions of adjustment.

8. An expansible shoe form comprising a thin-walled hollow resilient shell having a smoothly continuous outer surface engageable with the inner surface of a shoe, and an expander bar extending transversely across the shell, and means connecting the opposite ends 20 of the bar to the shell, one end at least of the bar being movable longitudinally of the shell thereby to vary the effective width of the rear part at least of the shell, the means connecting said movable end of the bar to the shell comprising locking elements for retaining the bar in any of a plurality of positions of adjustment.

9. An expansible shoe form comprising a thin-walled hollow resilient shell having a smoothly continuous outer surface engageable with the inner surface of a shoe, and an expander bar extending transversely across the shell, means pivotally connecting one end 35 of the bar to one side of the shell, an element at the opposite end of the bar arranged to engage and slide along an elongate slot in a part of the shell, and a spring tending to swing said expander bar thereby to move said element toward one end of the slot.

45 10. An expansible shoe form comprising a thin-walled hollow resilient shell having a smoothly continuous outer surface engageable with the inner surface of a shoe, an expander bar extending transversely across the shell, means pivotally uniting one end of the bar to one end of the shell, a pin carried by the other end of the bar, the shell having a flange member provided with a curved slot into which said pin projects and along which 50 the pin may slide, said slot having a notch in its outer edge for the reception of the pin, and a thrust bar pivotally connected to the expander bar and having a member at its other end for engagement with the counter portion of a shoe.

11. A shoe form comprising a hollow thin-walled resilient shell adapted to fit within the fore part of a shoe, and a resilient thrust bar secured at one end to said shell and comprising an element engageable with the inner sur-

face of the counter portion of the shoe, said thrust bar having a wire core encased in a celluloid tube.

Signed by me at Boston, Massachusetts, this 15th day of March, 1928.
